UNITED STATES PATENT OFFICE.

THOMAS B. JEFFERY, OF RAVENSWOOD, ILLINOIS.

VELOCIPED.

SPECIFICATION forming part of Letters Patent No. 408,014, dated July 30, 1889.

Application filed May 3, 1888. Serial No. 272,736. (No model.)

To all whom it may concern:

Be it known that I, THOMAS B. JEFFERY, a citizen of the United States, residing at Ravenswood, in the county of Cook and State of Illinois, have invented certain new and useful Improvements in Velocipedes, which are fully set forth in the following specification, reference being had to the accompanying drawings, forming a part thereof.

10 In the drawings, Figure 1 is a perspective. Fig. 2 is a plan of the main frame. Fig. 3 is an elevation of the same, in which appear, also, the pedal-supporting frame-bars. Fig. 4 is a detail side elevation of the brake mechanism. Fig. 5 is an axial section through the rear brake-rod bearings. Fig. 6 is a detail vertical section through the frame at the line x x on Fig. 3, showing the axle-bearing box in elevation. Fig. 7 is a section at the line x' x' on Fig. 6. Fig. 8 is an axial section through the ball-bearing of the main axle. Fig. 9 is a vertical section in a direction fore and aft through the seat of the pedal-crank-shaft bearing. Fig. 10 is a detail plan of a clip by means 15 of which the steering-rod is secured to the frame, a portion of the frame-bar being shown in said view. Fig. 11 is a transverse section at the line y y on Fig. 8.

The main frame of this machine comprises 20 two side bars A' and A^2 , a cross-bar A^3 , which rigidly unites them in the vicinity of the main axle-bearing, an upwardly-arched cross-bar A^4 , which further rigidly unites them forward of the main axle, downwardly and rearwardly extending arms A^5 A^5 , which project in the vertical plane of the side bars from the junctions of the cross-bar A^3 with said side bars, respectively, downwardly and rearwardly, and at their free extremities are provided with seats for the bearings of the rear-pedal crank-shaft. As illustrated, the bars A^5 A^5 have formed integral with them, at their upper end, in the immediate vicinity of their junction with the side bars and the cross-bar 25 A^2 , the seats A^{50} for the main driving-axle. These seats will be hereinafter explained in detail, together with certain adjusting devices which pertain to them. The main axle B extends across between the two side bars as 30 nearly in the vicinity of the cross-bar A^3 as

the necessary size of the parts permits, said axle extending underneath said side bars, while the cross-bar is in the same horizontal plane with them.

The main sprocket-wheel C is secured to 55 the axle B outside of the vertical plane of the side bar A' and inside the vertical plane of the right-hand drive-wheel D , and said drive-wheel is located as near to the vertical plane of the side bar A' as is consistent with that construction. The side bar A' extends forward from the cross-bar A^3 and constitutes a reach to the steering-head E , which is secured to its forward end. From the cross-bar A^3 said side bar A' extends rearwardly a 60 short distance and then bends upward, still extending rearward, and after extending a short distance in that direction it bends sideward or inward and extends toward the opposite side, but stops short of the middle point 65 between the wheels. To this sideward extension A^{10} there is secured the clip a^{10} , in which is adjustably secured the rear seat-support F . A similar clip a^{10} is secured upon the upwardly-arched cross-bar A^4 , and affords means 70 for adjustably securing the forward seat-support F , which is in all respects precisely similar to the rear support F . The brake-wheel C' is secured to the axle in a position relative 75 to the left-hand drive-wheel D' , similar to that which the sprocket-wheel C occupies with respect to the right-hand drive-wheel D .

To the main frame, in the close vicinity of the main axle, and preferably, as illustrated, 80 upon the lugs a^{50} , projecting from the seats A^{50} , are pivoted the forward pedal-crank-shaft frame-arms A^6 A^6 , which have seats for the self-aligning bearing-boxes of the forward 85 pedal crank-shaft K . The side bar A^2 extends forward from its junction with the cross-bar A^4 , and rearward from its junction with the cross-bar A^3 a short distance, and at its two extremities it is similarly provided with the bearings A^{20} and A^{21} , respectively, for the 90 brake-rods H and H' . Said brake-rods have 95 secured to them above their bearings, respectively, the crank-arms h and h' , whose ends are connected by the brake-link H^2 . Said brake-link has a threaded portion h^2 intermediate located between its ends, upon which 100

are placed two nuts H³. The brake-lever H⁴ is pivoted upon a clip A⁶¹, secured upon the left-hand pedal-crank-frame arm A⁶, and has connected to it the two ends of the brake-band C¹⁰, one end being connected one side of the pivot and the other the other side. The 5 brake-lever H⁴ is bent so that it has two arms H⁴⁰ and H⁴¹, the arm H⁴⁰ extending up and being forked at its upper end, said fork extending 10 up to the brake-link H², and having an eye through which said brake-link passes, the parts being assembled with the eye located between the two nuts H³. The points of connection of the two ends of the brake-band and 15 the brake-lever when the band is slack are not far out of line with the center of the brake-wheel, and when the brake is tightened by rocking the lever one end of the brake-band is carried inside the other and the band 20 is wrapped almost entirely around the brake-wheel. The large amount of surface which thus receives the pressure of the band renders less force necessary to operate the brake, and the band, being drawn from both ends, renders 25 less motion necessary to apply the necessary pressure to the brake-wheel.

The cranks h' are formed with the hubs h¹⁰, which extend through the bearings A²⁰ and A²¹, respectively, and at their lower end, 30 below said bearings, a collar h¹¹ is secured upon said hubs by the screw h¹², which at the same time binds the said hubs, and thereby the cranks h', to the brake-rod H'. By this means a large bearing-surface is obtained instead of a small one—viz., that of the hub instead of the rod. The collar h¹¹ constitutes a 35 stop to prevent the crank-hub, and so the rod h', from being lifted out of the bearing, and the crank H' above said bearing affords a 40 stop in the other direction.

The forward pedal-crank-shaft frame-arms A⁶ A⁶, pivoted, as above described, to the main frame, and carrying at their forward ends the crank-shaft K, are adjustably secured to the frame by the links A⁷ A⁷, which are bolted to clips A⁷⁰, secured on the side bars A' and A², and have several holes a⁷, through any of which a bolt may be passed to secure the links to the clips A⁷¹, which are provided on the frame-arms A⁶. By this means the 5 forward end of the said frame-arms may be raised and lowered, and secured at any desired height, thereby supporting the pedal crank-shaft K at any desired height to accommodate the rider occupying the forward seat.

The seat-supports F are formed of spring-metal rod, which is bent so that it consists of a vertical part F', which is inserted through 10 the clamp-socket in the clip a¹⁰; the oblique part F², which extends from the lower end of the vertical part upward and rearward to a point somewhat higher than the upper end of the vertical part, and the part F³, which extends from the upper end of the oblique part F² forward and preferably slightly upward, and has secured upon it the saddle L. This form of

support, while permitting the vertical adjustment of the seat to any desired height within the range of the straight vertical portion F', 70 gives to the seat elasticity of movement fore and aft and up and down, the former movement being obtained chiefly by the bend at the lower end of the parts F' and F², and the latter chiefly by the bend at the upper end of the part F² and rear end of the part F³.

To the side bar A' there are secured two clips A¹¹ A¹¹, which are alike, one being located a short distance forward of the upwardly-arched cross-bar A⁴, and the other 80 about an equal distance rearward of the straight cross-bar A³. These clips have vertical bearings a¹¹ for the steering handle-rods J J, and the horizontal bearing a¹² for the steering connection rod or link J'. The 85 steering-wheel M is journaled in the usual manner in the fork M', which is pivoted in the steering-head E, the axis of said pivot being substantially in the vertical plane of the side bar A'. The wheel M, therefore, does 90 not track precisely with the drive-wheel D, but is nearly enough to the vertical plane of the latter so that in ordinary road the two will run in the same beaten track. The rear seat, it will be noticed, being supported 95 at the inner end of the sideward extension A¹⁰ of the side bar A', is at the right-hand side of the middle line between the drive-wheels, and by the amount of distance which said sideward extension projects 100 laterally from the vertical plane of the side bar A' said rear seat is out of line with the steering-wheel M. The forward seat is secured upon the cross-bar A⁴ about as far to the left of the middle line between the wheels 105 as the rear saddle is to the right of that position, and is therefore out of line both with the rear seat and with the steering-wheel. The side bars A⁶, being in the vertical plane of the side bars A' and A², present no obstruction 110 forward of the forward seat, making the machine entirely "open front," said side bars being pivoted to the main frame very near to the drive-wheel axle and extending forward in a direction which deviates comparatively 115 little from horizontal. The raising and lowering of said side bars only very slightly changes the position of the crank-shaft forward or back, the adjustment being therefore almost entirely confined to the raising and 120 lowering and not materially affecting the slackness of the driving-chain N in any extent of adjustment which will ever be required, so that no adjustment of the chains themselves is ever necessary on account of 125 the adjustment of the position of the pedal crank-shaft.

I provide both for the pedal crank-shaft and for the axle self-aligning journal-boxes, those of the crank-axle being indicated in the 130 drawings by the letter B' and those of the crank-shafts by the letter B². In respect to their self-aligning capacity they are the same, and that quality is derived through the chair-

acter of the seats which are provided for them. The seat A^{50} for the journal-boxes B' of the main axle and the seats A^{61} for the pedal crank-shaft are shown, respectively, in Figs. 6 5 and 9. They consist of cavities large enough to receive said journal-boxes, and having inserted through one side a set-screw P , which has in its end a spherical concavity to fit the exterior surface of the journal-box. The opposite side of the cavity from that through which the screw is inserted is similarly provided with the spherical concavity fitting the outer surface of the journal-box, so that when said journal-box is put in place and the set-screw P tightened up against it it is retained by the said cavities, but is free to adjust itself in every direction about the center of the spherical curvature of said cavities, so that they may come into complete alignment with each other and with the shaft journaled in them.

For the main axle, which has ball-bearings in the self-aligning journal-boxes described, I provide a novel means of adjustment. The 25 conical sleeve R , which is interiorly threaded and screwed onto the exteriorly - threaded sleeve or bushing R' , has heretofore been held in place and adjusted by the jam-nut, also screwed onto the bushing outside of the conical sleeve. Where this construction is employed, there is liability of tightening up the adjusting - sleeve in setting the jam - nut against it, and thereby binding the ball-bearing too tightly. I prevent this damage by 30 providing a washer R^2 , which has projecting from its inner circumference a tooth r^2 , which enters the longitudinal groove r' , which I make in the outer portion of the bushing R' . By means of the engagement of this tooth r^2 35 in the groove r' the washer R^2 is prevented from turning about the bushing, and when the conical sleeve R has been screwed up to the proper position the washer R^2 , intervening between said sleeve and the jam-nut R' , 40 being incapable of turning, prevents the rotary motion of the jam-nut from being communicated to the adjusting-sleeve while the former is being tightened up against the washer, which in turn bearing against the 45 sleeve binds it firmly. This device may be applied to any similar adjustable ball-bearing.

I claim—

1. In a velocipede, a main frame comprising a fore-and-aft bar located at one side in close proximity to one of the drive-wheels and extending rearward and then sideward toward the other wheel and stopping short of the middle point between said wheels, and a seat 55 secured upon said sideward extension, substantially as set forth.

2. In a velocipede, a main frame comprising two side bars adjacent to the drive-wheels, respectively, the longer one of said side bars 60 extending forward and constituting a reach to the steering-head, and extending rearward and then sideward and stopping short of the

middle, a cross-bar connecting said side bars forward of the axle, and two seats, one supported upon the sideward extension of the 70 said longer side bar nearer to the vertical plane of said longer bar than to the vertical plane of the shorter bar, and the other seat supported on said cross-bar nearer the vertical plane of the shorter side bar, substantially as set forth. 75

3. In a velocipede, a main frame comprising two side bars and a cross-bar connecting them in the vicinity of the axle, one of said side bars extending upward in the rear of the 80 vertical plane of the axle and then sideward toward the vertical plane of the other side bar, but stopping short of the middle point between said bars and a second bar connecting said side bars forward of the axle and 85 arched upwardly between them, and two seats, one secured on the elevated sideward extension of the first-mentioned side bar and located nearer said bar and the other secured upon the upwardly-arched cross-bar nearer to 90 the other side bar, substantially as set forth.

4. In a velocipede, in combination, substantially as set forth, a pair of rear drive-wheels, a forward steering - wheel, a main frame, and two seats, the said seats being out 95 of line fore and aft with each other, and the steering-wheel being out of line with both drive-wheels and both seats and being located between the vertical plane of one of the seats and the vertical plane of the drive - wheel 100 which is nearest thereto.

5. In a velocipede, in combination with the main frame and the main axle journaled therein, the pedal-crank-shaft frame-bars A^6 , pivoted to the main frame in the vicinity of 105 the axle and extending thence forward, the pedal crank-shaft journaled at the forward part of said frame-bars, the sprocket-wheels on the main axle and crank-shaft, respectively, and the drive-chain connecting them, 110 said frame-bars being adjustably secured to the main frame at a point other than their pivot, whereby the height of the pedal crank-shaft may be varied at will without materially changing its position fore and aft or materially slackening or tightening the drive-chain, substantially as set forth. 115

6. In a velocipede, in combination with the main frame comprising two side bars located in proximity to the drive-wheels, respectively, 120 the forward pedal-crank-shaft frame-bars located in the vertical planes of said side bars, respectively, whereby said frame is rendered open front, substantially as set forth.

7. In a velocipede, in combination with the main frame having side bars located in proximity to the drive-wheels, respectively, the front and rear pedal-crank-shaft frame-bars located in the vertical planes, respectively, of the said side bars, whereby said frame is rendered open both front and rear, substantially as set forth. 125 130

8. In a velocipede, the seat-support consisting of a spring-rod having the vertical straight

part F' and the oblique part F² extending upward and rearward from the lower end of the vertical part, and the part F³ extending forward from the upper end of the oblique part 5 and adapted to receive the saddle, substantially as set forth.

9. In combination with the frame having the vertical socket a¹⁰, a seat-support having the vertical part F' inserted in said socket, 10 oblique part F² extending upward and rearward from the lower end of the vertical part, and the part F³ extending forward from the upper end of said oblique part, and the saddle secured upon said part F³, substantially 15 as set forth.

10. In a two-seated velocipede, in combination with the main frame and the main axle

journaled therein, two brake handle-rods journaled in the main frame, cranks on said handle-rods, respectively, and a link or rod 20 which connects said cranks, and a brake-lever and suitable brake operated thereby, said lever extending in proximity to the connecting-rod, and said rod being provided with adjustable stops to engage said lever upon both 25 sides, substantially as set forth.

In testimony whereof I have hereunto set my hand in the presence of two witnesses, at Chicago, this 27th day of April, A. D. 1888.

THOS. B. JEFFERY.
